UNITED STATES PATENT OFFICE

2,458,561

PLATE DEVELOPER

James T. Campbell, Detroit, Mich.

Application October 31, 1945, Serial No. 625,712

3 Claims. (Cl. 257—4)

1

This invention relates to a developing tank, and more particularly to a photographic plate developing mechanism characterized by means for maintaining a uniform tank temperature.

Heretofore, in plate developing apparatus and in the development of sensitized metal printing plates, considerable difficulty has been experienced in obtaining uniformity of quality. This has been due to changing temperature conditions which heretofore have been compensated for by variations in the developing time.

It is the principal object of this invention to provide refrigerating and heating units in conjunction with the developing tank to maintain a close differential in temperature in all seasons and in all weather. Thus a constant developing time can be established which is not subject to the varying weather conditions and temperature, which heretofore varied the developing time and required guessing as to the proper developing time.

As the developing time varies with changes of temperature and humidity the workman was continually confused and uncertain as to the exact procedure to follow in this important operation. The present invention is therefore adapted to provide for a substantially uniform tank temperature with a resultant constant developing time eliminating all guesswork.

It is the object of this invention to provide a substantially vertical insulated plate developing tank, together with heating and cooling means therefor, to regulate the tank temperature.

It is the object of this invention to provide regulatable thermostatic means in conjunction with said heating and cooling means for maintaining a substantially uniform tank temperature.

It is the further object of this invention to provide a dual thermostat switch characterized by separately rotatable temperature regulating dials for said heating and cooling means, together with a connecting link between said dials whereby a fixed temperature differential is maintained therebetween, regardless of their adjustment.

These and other objects will be seen from the following specification and claims in conjunction with the appended drawings, of which:

Fig. 1 is a side elevational view of the plate developer.

Fig. 2 is a top plan view thereof rotated 90 degrees counter-clockwise.

Fig. 3 is a front elevational view thereof, and

Fig. 4 is an enlarged elevational view of the thermostat control panel, and

Fig. 5 is a diagrammatic view illustrating the

2

switch, its temperature responsive elements and the electrical connections for controlling the heating and cooling means.

It will be understood that the above drawings illustrate merely one preferable embodiment of the invention and that other embodiments are contemplated within the scope of the claims hereinafter set out.

Referring to the drawings, Fig. 1, a motor base 11 of hollow construction is shown. Hollow tank frame 12, with removable bottom member 13, has an angularly formed anchor plate 14 welded or otherwise secured thereto adjacent the lower longitudinal edge thereof. Tank 12 is angularly arranged and supported at the end of base 11 with the horizontal portion of anchor plate 14 being secured to the top of said base by a plurality of spaced screws 15.

Hollow developing tank 16 with steel false bottom 18 is positioned within tank frame 12 in spaced relation to its side walls. The upper portion of tank 16 flares outwardly at 19 and is bent down at points 20 to fit over the front, rear and side walls of frame 12 for support thereon.

The front portion 21 of tank 16 extends upwardly as shown in the drawing. The rearward portion of tank 16 has a pair of upwardly extending spaced ears 22 providing a pivotal support at 23 for the two spaced members 24 which extend rearwardly from pivotal cover 25, with handle 26.

Copper cooling coil 27 is soldered or otherwise secured to the rear wall of tank 16, and is adapted to carry a refrigerant supplied to one end of said coil from an expansion valve not shown within box 28 carried on the rear wall of frame 12.

A condenser 29 is shown diagrammatically positioned on base 11 for supplying a liquid refrigerant to said expansion valve. Compressor 30 and operating motor 31 are likewise positioned on base 11 and associated with condenser 29 to make a completely operative refrigerating unit supplying refrigerant to cooling coil 27. The detail and operation of said refrigeration unit, per se, forms no part of the present invention except as a unit or element in itself forming a part of the combination set out herein; and consequently its detail and operation are omitted herein.

Referring to Fig. 1, a heating coil 32 is wound around the lower portion of tank 16 and consists of an enclosed electric resistance heating cable controlled by a suitable thermostat. Said thermostat is responsive to the setting of dial 33 on dual thermostat switch 34 shown in Fig. 4 with its cover 17 removed. Similarly, the refrigerating unit 27, 29, 30 and 31 is controlled by a suit-

able thermostat which is regulated by rotatable dial 35 on switch 34.

Switch 34, shown enlarged in Fig. 4, is illustrated in Fig. 1 supported on bracket 36' and having a cover 17. Referring to Fig. 4, the coolant control dial 33 and heater control dial 35 are calibrated in degrees, and are set relatively to the two indicating arrows 36.

From Fig. 4 it is seen that dial 35 is set at 67° and dial 33 at 65°, whereby when the temperature of the developing fluid in tank 16 drops below 65°, the heater coil 32 will be energized. Similarly, should the temperature of the developing fluid rise above 67°, the refrigerating unit motor 31 will be energized. It will be seen that preferably a two-degree differential is maintained between the heating and cooling units so that the situation of both units operating simultaneously is avoided.

Dials 33 and 35 are initially set using a thermometer in the fluid tank 16 by rotatably adjusting inner dials 37 and 38 and tightening screws 39. Dials 33 and 35 may now be rotatably adjusted and set for any desired temperature.

Dials 33 and 35 may be adjusted manually by inserting a screwdriver through a corresponding opening in switch cover 17 and into disc recess 40. Connecting link 41 respectively joins dials 33 and 35 by screws 42 and 43 whereby said dials are synchronized to rotate in unison. Thus a fixed 2-degree or other spacing is constantly maintained between said dials to guarantee that both heating and cooling units will not be simultaneously energized. The rotary adjustment of dial 35 effects a simultaneous correct and corresponding adjustment of dial 33. Figure 5 is a diagrammatic view illustrating the thermostat 52 with contact element 53 for energizing compressor operating electric motor 31 for controlling the cooling means 27. A second thermostat switch 54 with contact element 55 is employed for energizing the electric resistance coil 32 for controlling said heating element.

Referring to Fig. 1, with tank 16 inserted in frame 12, the space 44 therebetween is filled with a suitable insulating material 45 before bottom 13 is secured in place. Tank 16 is so well insulated that a neutral temperature is maintained a substantial part of the time between the two temperature settings of dials 33 and 35. Consequently, most of the time neither heating nor cooling unit will be energized.

Referring to Fig. 1, curved motor cover 46 has a flange 47 at its upper end which is secured to the rear wall of tank frame 12 by screws 48. The lower edge of cover 46 has a flanged portion 49 secured to base 11 by screws 50. Spaced screen members 51 are secured to the side wall edges of

cover 46 for completely enclosing the operating mechanism of the plate developing unit, at the same time permitting the free circulation of air therethrough.

Having described my invention, reference should now be had to the claims which follow for determining the scope thereof.

I claim:

1. A plate developer comprising a base, a refrigerating mechanism supported thereon, a hollow rectangular angularly arranged frame secured thereto, a hollow developing tank suspended within said frame in insulated and spaced relation thereto, cooling means secured to the wall of said tank and joined to said refrigerating mechanism, and heating means positioned around a portion of said tank.

2. A plate developer comprising a base, a refrigerating mechanism supported thereon, a hollow rectangular angularly arranged frame secured thereto, a hollow developing tank suspended within said frame in insulated and spaced relation thereto, cooling means secured to the wall of said tank and joined to said refrigerating mechanism, heating means positioned around a portion of said tank, and a thermostat switch carried by said frame and joined to said heating and cooling means for separately energizing the same at predetermined temperatures.

3. A plate developer comprising a base, a refrigerating mechanism supported thereon, a hollow rectangular angularly arranged frame secured thereto, a hollow developing tank suspended within said frame in insulated and spaced relation thereto, a cooling coil secured to a wall of said tank and joined to said refrigerating mechanism, an electric resistance coil positioned around a portion of said tank, a thermostat switch, a rotatable temperature calibrated dial on said switch electrically joined to said refrigerating mechanism, a rotatable temperature calibrated dial on said switch joined to said resistance coil, and a synchronizing link interconnecting said dials whereby, on rotary adjustment of one the temperature differential setting therebetween is maintained.
